UNITED STATES PATENT OFFICE

FRED SPENCE, OF SALE, ENGLAND, ASSIGNOR TO LINOTYPE AND MACHINERY LIMITED, OF LONDON, ENGLAND, A BRITISH COMPANY

MECHANISM FOR INKING THE PRINTING SURFACES OF ROTARY INTAGLIO PRINTING MACHINES

Application filed May 12, 1931, Serial No. 536,711, and in Great Britain May 16, 1930.

This invention relates to mechanism for inking the printing surfaces of rotary intaglio printing machines and has for its object so to construct such mechanism as to provide new or improved facilities for cleaning the ink roller and regulating the supply of ink to the said roller.

With this object in view, in carrying out the invention, the spindle of the inking roller is so mounted as to be adjustable to bring the inking roller into and out of contact with the printing surface without disturbing the driving connections of the said roller, and the ink trough is also adjustable into and out of operative position, the movement of the trough out of operative position being arranged to bring said trough into alignment with tracks to facilitate its removal from the machine when desired.

The invention is hereinafter more particularly described with reference to the accompanying drawings illustrating sufficient of a rotary intaglio printing machine to show the application thereto of a preferred constructional form of apparatus according to the invention.

In the said drawings:—

Figure 1 is a front elevation, partly broken away;

Figure 2 is a central vertical section, looking in the direction of the arrow A in Figure 1, and

Figure 3 is a corresponding vertical section looking in the direction of the arrow B in Figure 1.

The machine chosen for illustration comprises side frames 1, an impression cylinder 2 and plate cylinder 3, the printing plate on the latter being inked by a roller 4, which in the normal operation of the machine is rotated within an ink trough 5.

According to the invention, the inking roller 4 is carried on a spindle 6 journalled at its opposite ends in the downwardly extending arms of two swingable brackets or frames 7 which are co-axially pivoted each to the respectively adjacent side frame 1 of the machine.

Each bracket 7 is provided with a substantially horizontal arm 8, one of which (that

shown at the left-hand side of Figure 1, and in Figure 2) is in linked connection with a hand lever 9 hereinafter more particularly described.

The pivotal axis of the brackets 7 is co-axial with that of two rigidly connected toothed wheels 10 and 11, (Figures 1 and 2). The wheel 10 meshes with a toothed wheel 12 co-axial with, and fast to, the plate cylinder 3, and the wheel 11 is in positive driving connection, through intermediate gears 13, 14 with a pinion 15 fast on the ink roller spindle 6.

The intermediate gears 13, 14, are fast to a short shaft 16 journalled in the respective bracket 7. The ink roller pinion 15 and the wheel 14 meshing therewith, are enclosed within a casing 18 to protect them from contact with the ink in the trough 5.

The before-mentioned hand lever 9 is fast on one end of a rock shaft 19 extending transversely of the machine, while on the other end of this shaft is secured an arm 20 (see particularly Figure 3) in linked connection with the second of the two before-mentioned arms 8. The two links 21 connecting the arms 8 with the hand lever 9 and arm 20, are each formed in two parts adjustably connected together by a turnbuckle 22, by means of which the setting of the ink roller 4 relatively to the plate cylinder 3 can be accurately and conveniently effected.

The hand lever 9 is located in close adjacency to a stationary bracket 23, and can be retained in either of its terminal positions by a pin 24 insertable through it and into holes in said bracket, while, moreover, the rock shaft 19 has fast thereon, a boss carrying two stop-arms 25, 26, the latter adjustable, which by contacting with a part of the machine frame, determine the said terminal positions and limit the extent of swing of the ink roller towards and away from the plate cylinder.

The ink trough 5 is carried at its ends on two supports or rails 27 which when the machine is running in printing condition, support the ink trough 5 in the position in which it is shown on the drawings, the ink roller 4 then lying within the trough.

To provide for free access to the ink roller and to the adjacent parts the rails 27 are adapted to be moved out of operative position to bring the trough away from the ink roller as hereinafter described. The rails 27 are provided with spring clips 28 which, by engagement with ribs or shoes 29 on the trough 5, serve to prevent the latter from being accidentally shifted on the rails 27 when in raised or normal position. When, however, the said rails are brought to their lowermost position, the clips 28 are brought into contact with fixed rails 27^a and are thereby released from the ribs 29 so as to leave the trough 5 free for removal.

The rails 27 are of such dimensions and arrangement that when they are in their lowermost position they align with, and form virtual continuations of, fixed horizontal tracks 30, so that the trough 5, when released from the rails as just described, can be slid off the latter and over the tracks 30, to a position remote from the ink roller 4, such movement of the ink trough, if desired, being sufficient to permit of its bodily removal from the machine.

The raising and lowering of the rails 27 may be effected by any suitable means. In the example illustrated in the drawings, said rails are secured to the upper ends of two vertical screws 31 guided in stationary brackets 32 and on which there are threaded two nuts 33, which, though revolvable, are secured against axial movement. Externally these nuts 33 are formed with spiral gear teeth to mesh with correspondingly toothed wheels 34, both fast to a transverse shaft 35. This shaft may be conveniently rotated by a chain 36 and sprockets 37 from a hand wheel 38 whose shaft is rotatable in a fixed bracket 39; preferably, this bracket 39 is provided with a pinching screw 40 adopted to engage said shaft and thereby lock the supporting rails 27 and trough 5 at any desired height.

Having described my invention, I declare that what I claim and desire to secure by Letters Patent is:—

1. In inking mechanism of rotary intaglio printing machines, the combination with an ink trough, an ink roller, and means operable to rotate the ink roller within the trough normally in contact with the printing surface on the plate cylinder, of bearings for the ink roller spindle, adjustable independently of the ink trough to bring the roller into and out of contact with the printing surface, without disturbing the driving connections through which the spindle is rotated.

2. In inking mechanism of rotary intaglio printing machines, the combination with an ink trough, an ink roller rotatable within the trough, and gearing operative to transmit rotary motion to the ink roller, of brackets rotatably supporting the ink roller spindle and angularly adjustable about the axis of

a member of the gearing to enable the ink roller to be swung into and out of contact with the printing surface on the plate cylinder, without disturbing the driving connections through which the ink roller is rotated.

3. In inking mechanism of rotary intaglio printing machines, the combination with an ink trough, an ink roller rotatable within the trough, a plate cylinder, a gear wheel operatively fast to the plate cylinder, and gearing operative to transmit rotary motion from the plate cylinder to the ink roller, of brackets rotatably supporting the ink roller spindle and angularly adjustable about the axis of a member of the gearing, to enable the ink roller to be swung into and out of contact with the printing surface on the plate cylinder, without disturbing the driving connections between the gear wheel fast to the plate cylinder and the ink roller.

4. Inking mechanism according to claim 2, characterized by a hand lever adjustable about a fixed axis, to effect the swinging of the ink roller, connecting means between that lever and the brackets supporting the ink roller spindle, and stops determining the operative and inoperative positions of the ink roller.

5. Inking mechanism according to claim 2, characterized by a hand lever adjustable about a fixed axis, to effect the swinging of the ink roller, connecting means between that lever and the brackets supporting the ink roller spindle, stops determining the operative and inoperative positions of the ink roller, and adjustable connections between the hand lever and the brackets for varying the operative position of the ink roller.

6. In inking mechanism of rotary intaglio printing machines, the combination with an ink trough, an ink roller, and means operable to rotate the ink roller within the trough normally in contact with the printing surface on the plate cylinder, of bearings for the ink roller spindle, adjustable independently of the ink trough to bring the roller into and out of contact with the printing surface, without disturbing the driving connections through which the spindle is rotated, and supports for the ink trough movable to bring said trough into and out of operative relation to the ink roller.

7. In inking mechanism of rotary intaglio printing machines, the combination with an ink trough, an ink roller, and means operable to rotate the ink roller within the trough normally in contact with the printing surface on the plate cylinder, of bearings for the ink roller spindle, adjustable independently of the ink trough to bring the roller into and out of contact with the printing surface, without disturbing the driving connections through which the spindle is rotated, supports for the ink trough movable to bring said trough into and out of operative relation

to the ink roller, and on and off which the trough can be slidden, and stationary tracks with which the supports are alignable and along which the trough can be traversed during such alignment.

8. In inking mechanism of rotary intaglio printing machines, the combination with an ink trough, an ink roller, and means operable to rotate the ink roller within the trough

10 normally in contact with the printing surface on the plate cylinder, of bearings for the ink roller spindle, adjustable independently of the ink trough to bring the roller into and out of contact with the printing surface,

15 without disturbing the driving connections through which the spindle is rotated, supports for the ink trough movable to bring said trough into and out of operative relation to the ink roller, and on and off which the

20 trough can be slidden, stationary tracks with which the supports are alignable and along which the trough can be traversed during such alignment, clips adapted to secure the trough on the supports, and abutments in the

25 paths of said clips adapted automatically to release the clips when the supports are aligned with the stationary tracks.

9. In inking mechanism of rotary intaglio printing machines, the combination with an

30 ink trough, an ink roller, and means operable to rotate the ink roller within the trough normally in contact with the printing surface on the plate cylinder, of bearings for the ink roller spindle, adjustable independently of

35 the ink trough to bring the roller into and out of contact with the printing surface, without disturbing the driving connections through which the spindle is rotated, supports for the ink trough movable to bring

40 said trough into and out of operative relation to the ink roller, and on and off which the trough can be slidden, stationary tracks with which the supports are alignable and along

45 which the trough can be traversed during such alignment, raising and lowering means for the ink trough supports, and locking means adapted to secure said supports in any desired position relatively to the ink roller.

50 In testimony whereof I have affixed my signature hereto.

FRED SPENCE.
